(57) **CLAIM**

The ornamental design for a bassinet, as shown and described.

DESCRIPTION

FIG. 1 is perspective view of the design for a bassinet of the present invention in an open configuration;

FIG. 2 is a left elevational view of the bassinet of FIG. 1;

FIG. 3 is a right elevational view of the bassinet of FIG. 1;

FIG. 4 is a top plan view of the bassinet of FIG. 1;

FIG. 5 is a bottom plan view of the bassinet of FIG. 1;

FIG. 6 is a front elevational view of the bassinet of FIG. 1;

FIG. 7 is a back elevational view of the bassinet of FIG. 1;

FIG. 8 is a perspective view of the bassinet of the present invention in a closed configuration;

FIG. 9 is a top plan view of the bassinet of FIG. 8;

FIG. 10 is a bottom plan view of the bassinet of FIG. 8;

FIG. 11 is a left elevational view of the bassinet of FIG. 8;

FIG. 12 is a right elevational view of the bassinet of FIG. 8;

FIG. 13 is a front elevational view of the bassinet of FIG. 8; and,

FIG. 14 is a back elevational view of the bassinet of FIG. 8.

The broken lines illustrated in the drawings form no part of the design.
